SIGNAL GENERATOR WITH SUPPLY VOLTAGE COMPENSATION

Philip H. Luft, Penn Township, Allegheny County, Pa., assignor to Westinghouse Air Brake Company, Wilmerding, Pa., a corporation of Pennsylvania

Application November 14, 1956, Serial No. 622,123

2 Claims. (Cl. 330—29)

My invention relates to a signal generator with supply voltage compensation and more particularly to a transistorized amplifier in which small variations in the operating voltage are compensated for so as to have little effect upon the output signal voltage.

In a signal generator in which a signal developed by an oscillator is to be amplified by an amplifier and in which the oscillator and amplifier are provided with operating voltages from a common source, the amplified signal usually varies in accordance with variations of the supply voltage. For example, if the operating voltages are supplied by a battery, the amplified signal decreases as the battery ages and increases when an old battery is replaced with a new one. In some applications of signal generators of the type embodying my invention it is essential that the output signal be maintained substantially constant and independent of such supply voltage changes. An application of this type occurs in railway signaling wherein a track circuit is formed, for the purpose of detecting when a vehicle is within certain sections of track, by connecting a signal generator or transmitter and a receiver to the track rails. The signal generator energizes the track rails with a current which flows along the track rails to the receiver. The receiver controls apparatus for indicating the presence or absence of a vehicle within the track section. When a vehicle is located a distance from the signal generator and receiver, the track rails present a high impedance to the signal current and prevent it from being shunted between the rails due to the shunt formed by the vehicle's wheels and axles and, accordingly, a clear indication is provided. However, when the vehicle approaches to within some predetermined distance of the signal generator and receiving apparatus, the signal is shunted through the shunt formed by the wheels and axles of the vehicle, and the apparatus controlled by the receiver responds accordingly to indicate the presence of the vehicle within the track section. Obviously, if the output from the signal generator varies from time to time, so would the distance to the point at which the vehicle's presence would be recognized. Since variations in the voltage of the supply source for such a signal generator causes variations in the output signal voltage, it is desirable to provide the signal generator with means for compensating for variations in the supply voltage.

It is therefore, an object of my invention to provide a signal generator with an output signal that is substantially independent of small variations of the operating voltage.

A further object of my invention is to provide a signal generator including a transistorized amplifier having

2

a variable gain such that the amplified signal decreases with increased operating voltage and conversely.

These and other advantages of my invention will be more clearly understood from the following description taken in connection with the accompanying drawing and the new and novel features thereof will be set forth in the appended claims.

The accompanying drawing is a diagrammatic view showing a signal generator provided with means embodying my invention for obtaining a constant output voltage.

The embodiment of the generator illustrated in the drawing comprises an oscillator 1 which generates a signal voltage to be amplified by amplifier 2. The amplified signal may, as here shown, be further amplified by a power amplifier 3. The useful output signal from the signal generator is obtainable at the output circuit of the amplifier, here designated by the reference character 4. The oscillator and amplifier are supplied with suitable operating voltages from a common source of direct current energy, here shown as a battery 5.

Amplifier 2 is a variable gain transistorized amplifier comprising an input transformer 6 which is provided with a primary winding 7 and a secondary winding 8. The primary winding is connected to the oscillator 1 in such manner that the transformer is energized by the signal voltage. The secondary winding is connected to a voltage dividing network here shown as series connected resistors 9 and 10. The common junction 11 of these two resistors is further connected to an emitter electrode 12 of a transistor 13. The end of the secondary winding 8 which is connected to resistor 10 is connected through a pair of series connected resistors 14 and 15 to a base electrode 16 of the transistor. Resistors 14 and 15 are by-passed by a capacitor 17 which has a low reactance at the frequency of the signaling current. The common junction of resistors 14 and 15 is connected to the positive terminal of battery 5. Collector electrode 18 of the transistor is connected through the primary winding 19 of a transformer 20 and a resistor 21, connected in series, to the base electrode. A common junction 22 between the resistor and primary winding is connected to the negative terminal of battery 5. Secondary winding 23 of the transformer 20 is connected to the input circuit of the power amplifier 3.

In a signal generator as here shown it is obvious that the signal voltage developed by amplifier 3 would fluctuate with variations of the voltage of battery 5 if supply voltage compensation were not provided. However, with my novel arrangement the rectifying characteristics of a transistor element are employed to compensate for such variations of the supply voltage. The emitter to base circuit of the transistor associated with amplifier 2 is arranged so that the gain of amplifier 2 is made to vary inversely as the voltage of battery 5. That is, an increase in the supply voltage results in a decrease in gain and vice versa.

Before proceeding with the description of the mode of operation of amplifier 2 it may be well to review briefly some of the internal characteristics of a transistor which are utilized in my invention to enable a better understanding of my invention. It is well known to those skilled in the art that the internal characteristics of a transistor such, for example, as the emitter to base circuit characteristics behave, insofar as an external circuit connected thereto is concerned, as a simple rectifying contact. The volt ampere characteristics of such a recti-

fying contact are highly non-linear. Inasmuch as the incremental resistance of such a rectifying contact is determined by the slope of the volt ampere characteristics at the point to which the emitter to base circuit is biased, the incremental resistance varies over a considerable range of values for various values of biasing voltage. When the emitter to base circuit, referred to hereinafter as a rectifying junction, is forward biased, the incremental resistance is relatively low and decreases as the bias voltage is increased within the normal range of bias voltages. When a junction is reverse biased, the incremental resistance is relatively high and ordinarily, remains more nearly constant than the forward biased junction, within reasonable limits of reverse bias voltage. It is the variation in the incremental resistance of a forward biased junction that is utilized in my invention to compensate for the variations of the supply voltage.

For the purpose of understanding the operation of my invention let it be assumed that the circuit is operating normally with a given battery voltage. Accordingly, the transistor is provided with proper operating voltages due to the voltages developed across resistors 15 and 21. The voltage drop across resistor 15 provides the operating voltage for the emitter to base circuit of transistor 13. This voltage biases this circuit in the forward direction, and the voltage developed across resistor 21 provides the operating voltage for the collector to base circuit of the transistor.

The oscillator provides the secondary winding 8 of transformer 6 with a signal voltage, a part of which is impressed upon the emitter to base circuit of the transistor. The part of the secondary voltage which is supplied to the emitter to base circuit is determined by the voltage dividing network comprising resistor 9 acting in series with the parallel combination of resistor 10 and the internal incremental resistance of the emitter to base circuit of the transistor (the impedance of capacitor 17 being negligible at the frequency of the signal current). This establishes a definite emitter to base signal voltage and, in accordance therewith, a signal voltage is developed in the collector to base circuit. This signal voltage passes through transformer 20 to the power amplifier 3 which, in turn, provides the output circuit with a signal voltage.

If the battery voltage decreases due, for example, to aging of the battery, the oscillator provides a signal voltage with decreased amplitude which would result in a decreased signal at the output circuit of amplifier 3 if compensation was not provided. Also amplifier 3 may have reduced gain with the lower operating voltage which would also decrease the output signal voltage. The decrease in supply voltage, however, decreases the forward bias on the emitter to base circuit of transistor 13 which results in an increased emitter to base incremental resistance. The increased incremental resistance changes the voltage dividing action of resistors 9 and 10 and the emitter to base circuit of the transistor. This causes a greater portion of the signal voltage induced in the secondary winding 8 of transformer 6 to appear across the emitter to base circuit of the transistor. The increased input signal voltage to the emitter to base circuit of the transistor results in a greater amplified signal in the collector to base circuit. Thus by proper proportioning of parts, the voltage developed at the output circuit of amplifier 3 can be maintained substantially constant.

An increase in the supply voltage such as would occur when the battery is replaced by a new battery has the opposite effect. That is, an increase in the battery voltage provides a greater bias voltage on the emitter to base circuit of the transistor, due to the increased voltage across resistor 15. The increased bias voltage lowers the emitter to base incremental resistance of the transistor and a smaller portion of the signal voltage induced in the secondary winding 8 appears across the emitter to

base circuit which compensates for the increased signal voltage developed by the oscillator.

It is to be understood that the current gain of the transistor (usually referred to in the literature as alpha) increases with an increase in the battery voltage due to the increased supply voltage to the collector to base circuit and decreases with decreased supply voltage. These changes in current gain, however, are more than compensated for by the voltage dividing action of resistors 9 and 10 and the incremental resistance of the emitter to base voltage. Accordingly, it is the overall gain of the amplifier stage represented by the reference character 2 which compensates for the variations of the battery voltage.

It should be clear that while the drawing shows the use of a transistor of the P-N-P variety in the compensating amplifier, that a transistor of the N-P-N variety may, equally as well, be used by merely reversing the polarity of the operating voltage supply. Furthermore, while the drawing shows the use of a transistor in a circuit arrangement that is usually referred to as a common base circuit, other circuit arrangements such as common emitter or common collector circuit may also be employed.

Although I have herein shown and described only one form of supply voltage compensating means embodying my invention, it is to be understood that various changes and modifications may be made therein within the scope of the appended claims without departing from the spirit and scope of my invention.

Having thus described my invention, what I claim is:

1. A compensating circuit for providing a substantially constant amplitude signal comprising an oscillator generating a signal voltage, a transistor including an emitter, a base, and a collector electrode connected to amplify said signal voltage, said oscillator and said transistor adapted to be connected to a common battery for obtaining proper operating and biasing voltages therefrom, the battery being susceptible to voltage variations, the amplitude of said signal output from said oscillator being proportional to the battery voltage, a voltage dividing network comprising an impedance having at least first and second portions connected in series and the emitter to base circuit of said transistor connected in parallel with said second portion, the incremental impedance in said emitter to base circuit varying inversely with the biasing voltage derived from the battery, and means impressing the generated signal across said network, said network effecting a voltage division to cause the signal impressed across said emitter to base circuit to be inversely related to the amplitude of the generated signal thereby to compensate for variations in the amplitude of the generated signals due to variations in the battery voltage.

2. A compensating circuit for providing a substantially constant amplitude signal comprising means generating a signal voltage, a transistor including an emitter, a base, and collector electrodes, said signal generating means and said transistor being adapted to be connected to a common source of direct current energy for obtaining proper operating voltages therefrom, the direct current energy source being susceptible to voltage variations, the amplitude of said signal output from said signal generating means being proportional to the voltage of said source of energy, a voltage dividing network including at least first and second impedances connected in series and the emitter to base path of said transistor connected in parallel to said second impedance, and means impressing said input signal across said network, the incremental impedance existing between said emitter to said base being inversely related to the voltage of the source of energy, any variation in said incremental impedance due to variations in the source voltage causing a change in the voltage dividing action of said network whereby the signal voltage effectively impressed across

said emitter to base varies inversely with the change in voltage of the source of energy.
